(57) **CLAIM**

The ornamental design for a handle for a utensil, as shown and described.

DESCRIPTION

FIG. 1 is a symmetrical view of the handle for a utensil showing my new design;

FIG. 2 is a cross-section view taken along line 2—2 of FIG. 1;

FIG. 3 is a cross-section view taken along line 3—3 of FIG. 1;

FIG. 4 is a cross-section view taken along line 4—4 of FIG. 1;

FIG. 5 is an end view taken from the left of FIG. 1; and, FIG. 6 is an end view taken from the right of FIG. 1.

The broken lines shown in the drawings are for illustrative purposes only and form no part of the claimed design.
